UNITED STATES PATENT OFFICE.

CHARLES D. McDONALD, OF SEATTLE, WASHINGTON.

PORTABLE FOLDING BED.

1,405,141.

Specification of Letters Patent. Patented Jan. 31, 1922.

Application filed October 26, 1920. Serial No. 419,672.

To all whom it may concern:

Be it known that I, CHARLES D. McDONALD, a citizen of the United States, residing at Seattle, in the county of King and State 5 of Washington, have invented a certain new and useful Improvement in Portable Folding Beds, of which the following is a specification.

My invention relates to improvements in 10 portable folding beds and the object of my invention is to provide a bed which may be easily and rapidly assembled and disassembled, and which may be readily folded into a small compact package when not in 15 use and carried on the running board of an automobile.

Another object is to provide a bed comprising spreading and bracing members adapted to secure same in a rigid position 20 when in use.

A further object is to provide a portable folding bed embodying novel hinge connections for the leg members thereof.

A still further object is to provide a bed 25 adaptable for camp use which is light, simple and durable, and which may be manufactured at a minimum cost.

With the above and other objects in view which will appear as the description proceeds the invention consists of the novel construction, adaptation, arrangement and combination of parts hereinafter described 30 and claimed.

I accomplish these objects by devices illustrated in the accompanying drawings, wherein—

Figure 1 is a top plan view of a bed embodying the features of my invention.

Fig. 2 is a view in side elevation of same.

40 Fig. 3 is a view in end elevation of the bed taken from the foot end thereof.

Fig. 4 is a view in side elevation of a transverse supporting member.

Fig. 5 is an enlarged fragmentary view in 45 cross section taken on a broken line 5, 5 of Fig. 2.

Fig. 6 is an enlarged fragmentary view in perspective of the corner joints in disassembled relation.

50 Referring to the drawings, throughout which like reference numerals designate like parts, the numerals 10 and 11 designate two spaced apart side members which are connected in alignment by hinges 12 to similar 55 but shorter side members 13 and 14 respectively. The members 10 and 13 when extended constitute one side rail and the mem-

bers 11 and 14 constitute the other side rail of the bed.

A head member 15 is transversely disposed at the head of the bed and a similar foot member 16 is disposed at the foot of the bed.

The portion of the bed upon which the bodies of the occupants are supported is 65 preferably formed of a rectangular piece of canvas 17, the head end of which is secured around a transverse wire rod 18 which wire rod is yieldingly secured to the head member 15 by equi-distantly spaced spiral 70 springs 19, the inner ends of which are secured to the said rod 18. The opposite or outer ends of the said springs are secured to screw eyes 20 which are screwed into the head member 15. 75

The foot end of the said canvas is secured around a transverse take up member 21 the flanged ends of which rest upon the side members 13 and 14. The transverse member 21 is adjustably secured to the foot member 80 16 by bolts 22 provided with wing nuts 23 by means of which the canvas may be stretched to the desired tension.

The edge portions of the canvas adjacent to the head portion where the greatest 85 weight of the occupants is supported is provided with flaps 24 which pass around the side members 10 and 11 and are sewed to the said canvas substantially as shown.

Extending lengthwise along the under side 90 of the canvas 17 in the medial plane of the bed is a cable 25 which is secured to the head member 15 and the foot member 16 in such manner that when the canvas is stretched for occupancy the said cable will 95 have sufficient tension to prevent the said canvas from sagging in the middle thereby suitably adapting the bed for occupancy by two persons.

The outer ends of the head member 15 and 100 foot member 16 are provided with downwardly disposed plates 26 having slots 27 formed in their lower end portions. The said plates fit snugly within grooves 28 provided in the upper end portions of legs 29 105 and 30, and the slots 27 fit over bolts 31 which are transversely secured through the upper end portions of the said legs. The outer ends of the side members 10, 11, 13 and 14 are provided with tongues 32 which 110 fit snugly within grooves 33 formed in the outer ends of the head member 15 and foot member 16.

The two sides of the bed at the location

of the hinges 12 are provided with a transverse supporting member comprising a cross bar 34 having legs 35 functionally secured thereto by plates 36 having slots 37 therein 5 which fit over bolts 38 in the same manner previously described for the head and foot members.

The cross bar 34 is disposed far enough below the canvas 17 so as not to come in 10 contact with same when it is sagged by the weight of the occupants of the bed, blocks 39 being secured to the outer and upper end portions of the said bar 34. The said blocks are provided with shoulders 40 which hold 15 the side members in spaced relation and with dowels 41 which fit within holes in the side members 10 and 11.

The legs 29, 30 and 35 are braced against longitudinal movement of the bed by braces 20 42 formed of heavy wire. The lower ends of the said braces are bent at right angles and pivotally secured through the said legs while the upper ends are likewise bent at right angles and adapted to fit within 25 sockets 43 provided in the side members 10, 11, 13 and 14.

The said braces 42 being sufficiently resilient to thereby insure that the upper ends of the said braces will be positively retained 30 in their associated sockets 43 when the bed is erected.

The said legs are further braced against transverse movement by spring braces 44 made of heavy spring wire and having hooks 35 45 bent in their outer ends for engagement with bent staples 46 secured in the said legs. The inner ends of the said braces 45 are bent at right angles as at 47 and driven into the head and foot members 15 40 and 16 and into the cross bar 34 and are further secured thereto by staples 48 located adjacent to the said inner ends.

In dis-assembling the bed the head and foot members 15 and 16 are detached leaving 45 the legs 29 and 30, the canvas 17 together with the wire 18, transverse member 21 and fastenings attached thereto. The side members are slipped out of the flaps 24 and swung together at their hinged connections. The transverse supporting member is then detached leaving the legs attached thereto.

The legs of the head, foot and transverse supporting members are folded as shown in 55 Fig. 4 in dotted lines, the staples 46 sliding upwardly on the spring braces 44 and serving to hold the said legs in the folded position. The braces 42 which remain attached to the said legs are swung in alignment 60 therewith.

It will thus be seen that the bed has been dis-assembled into four separate parts, namely the head and foot members with the canvas and attachments which are rolled 65 together forming the first part, the two side

members forming the second and third parts, and the transverse supporting member constituting the fourth part.

These four parts are all of substantially the same length when their constituent members are folded together and are in convenient form to be placed together and secured in one compact package and carried on the running board of an automobile.

The simplicity, rigidity, durability and 75 constructive economy of this bed will be obvious.

From the foregoing description taken in connection with the accompanying drawings, the advantages of the construction and of the method of operation of my portable folding bed will be readily apparent to those skilled in the art to which the invention relates, but while I have described the principle of operation of the invention, together with the structure which I now consider to be the best embodiment thereof, I desire to have it understood that the structure shown is merely illustrative and that such changes may be made when desired as are within 90 the scope of the invention.

What I claim is:

A folding bed frame comprising two side frame members each formed of two parts pivotally connected by hinges located on the 95 upper sides thereof, a transverse supporting member located under the abutting ends of the said side frame members, the said transverse supporting member comprising a cross bar, blocks secured to the upper end portions of the said cross bar having shoulders therein adapted to receive and hold the said side members in spaced apart relation, dowels in the said shoulders adapted to register with holes in the said side members, a head 100 and a foot member each located at the opposite ends of the said side members, legs for supporting the said head, foot and transverse supporting members having grooves in the upper ends thereof, the outer ends 110 of the said head, foot and transverse supporting members being provided with downwardly disposed tongues having open ended slots in their lower end portions, the said tongues adapted to fit within the said grooves of the said legs, the said slots in the said tongues adapted to functionally engage bolts secured transversely of the said 115 legs through the upper end portions of the said legs, and the outer ends of the said side members having tongues adapted to fit within grooves provided within the outer end portions of the said head and foot members and to abut against the said tongues of the said head and foot members. 120

In witness whereof, I hereunto subscribe my name this 15th day of October, A. D. 1920.

CHARLES D. McDONALD.
